UNITED STATES PATENT OFFICE.

IGNATIUS LUCAS, OF PASSAIC, NEW JERSEY.

ERASING INSTRUMENT.

No. 878,735.

Specification of Letters Patent.

Patented Feb. 11, 1908.

Application filed February 26, 1907. Serial No. 359,441.

To all whom it may concern:

Be it known that I, IGNATIUS LUCAS, of Passaic, in the county of Passaic and State of New Jersey, have invented a new and useful Erasing Instrument, of which the following is a specification.

Grinding an erasing knife, such as is now in general use, successfully one will find quite difficult.

10 My invention relates to an improvement in an erasing instrument and the object of my invention is to produce an inexpensive erasing instrument that can be easily sharpened. I attain this object by an instrument 15 illustrated in the accompanying drawing, in which

Figure 1. is a side view of the instrument. Fig. 2. is a longitudinal cross section of the instrument. Fig. 3. is the bottom view. 20 Fig. 4. shows the instrument as held on an oil stone in sharpening the said erasing instrument. Fig. 5. shows the instrument as attached to a pen holder.

Similar letters refer to similar parts 25 throughout the several views.

A steel tube A. is cut diagonally across as shown in Fig. 1. and Fig. 2. forming the cut-

ting edges B. Figs. 1, 2, 3, which cutting edges by being rubbed on a grinding stone S Fig. 4. or other sharpening tools can be easily sharpened or resharpened; it being understood that the proper hardening of the cutting edges has been attended to during the procedure of the manufacture of the instrument. Although I have shown in the drawings a round tube for the purpose set forth it will be understood that an oval or square tube can also be used to attain the aforesaid object of my invention substantially as described above. Fig. 5 shows the 35 erasing instrument as attached to a pen holder P. with a protecting cap C.

Having thus fully described my invention I claim as new and desire to secure by Letters Patent.

An erasing instrument consisting in a tube terminating at an end in an oblong base oblique to the longitudinal axis of the said tube.

IGNATIUS LUCAS.
